UNITED STATES PATENT OFFICE.

EDGAR A. OPPENHEIMER, OF CHICAGO, ILLINOIS, ASSIGNOR TO NEWTON D. BAKER,
SECRETARY OF WAR, TRUSTEE.

DUPLICATOR.

1,382,312.

Specification of Letters Patent. Patented June 21, 1921.

Application filed April 17, 1919. Serial No. 290,794.

(FILED UNDER THE ACT OF MARCH 3, 1883, 22 STAT. L., 625.)

To all whom it may concern:

Be it known that I, EDGAR A. OPPENHEIMER, a citizen of the United States, and a resident of Chicago, in the county of Cook and State of Illinois, have invented an Improvement in Duplicators, of which the following is a specification.

The invention described herein may be used by the Government, or any of its officers or employees in prosecution of work for the Government, or by any other person in the United States without payment of any royalty thereon.

My invention relates to duplicators or hectographs in which a surface of absorbent material is utilized to reproduce writing or drawings, which are transferred to the surface of the material by means of a suitable reproducing ink.

20 The object of my invention is to provide a novel form of duplicator by the use of which several impressions can be successively made from a single duplicator.

Duplicators or hectographs, as heretofore constructed, have usually comprised a tray containing clay or similar material, which provides the absorbent surface. When it is required to reproduce a number of different sheets of writing or drawing within a short time, it is necessary to provide as many trays of absorbent material as there are sheets to reproduce, because of the fact that it takes several hours for the clay to absorb the reproducing ink, and it is obvious that a large number of such trays are awkward to handle, because of their bulk and weight. Other forms of duplicators have utilized rolls of gelatinized fabric, which, however, have been found difficult to handle when it is desired to successively reproduce a number of different sheets.

In my invention I provide a duplicator which comprises a tray containing a plurality of sheets of absorbent material by means of which a number of different sheets of writing or drawing can be successively reproduced.

The main object of my invention is to provide a container for the tray having means for clamping a sheet thereon to which

the writing or drawing to be duplicated may be transferred.

In the accompanying drawings:

Figures 1 and 2 are perspective views of a duplicator embodying my invention.

Fig. 3 is a central cross section of the device with the tray removed.

Fig. 4 is a central vertical longitudinal section, the tray removed.

Figs. 5, 6 and 7 are detailed views of the parts shown in Fig. 2.

Referring to the drawings, the duplicator consists of a box 1 of sheet metal, or other similar material, that is provided with a side door 2 mounted on hinges 3 and provided with a catch 4. The top 5 of the box 1 is provided at its ends with depressed portions to form steps 6 below the surface of the top 5. A tray 7 fits within the box between the steps 6 and the bottom of the box, as shown in Fig. 1. The top 5 is further provided with a hinge hasp 8 having an opening 9 to receive the catch 4 on the door 2, as best shown in Figs. 3 and 5. Clips 10 are secured to the steps 6 by means of hinges 11 and extend lengthwise of the steps. The clips 10 are adapted to be received in the depressions 12 at the ends of the steps 6, the depressions 12 being so formed as to tend to hold the clips therein by reason of the resiliency of the material forming the box. The clips 10 project at each end beyond the sides of the box 1, as best shown in Fig. 7, so that they may be removed from the depressions 12.

A plurality of sheets 13 of gelatinized fabric, or similar material, are contained in the tray 7 and are separated from each other by sheets 14 of paper or other similar material, of such a nature that the sheets will not stick to each other when moist or when subjected to abnormal temperatures. When it is desired to use the duplicator, the tray is removed from the box 1 and the top sheet 13 is placed on the top 5 and fixed in position by means of the clips 10, which force the end portions of the sheet 13 into the depressions 12. The writing or drawing to be reproduced is then transferred to the sheet 13 by means of reproducing ink, after

which, any number of copies are made from the sheet 13 in the usual manner.

If it is desired to successively reproduce a number of sheets of writing or drawing, 5 the inked sheet is removed from the top of the box and is placed at the bottom of the tray 7. In this way a number of sheets may be reproduced until the supply of duplicating sheets 13 is exhausted. The tray 10 is then left in the box 1 until the reproducing ink has been absorbed by the sheets 13.

From the foregoing, it is obvious that all 15 of the sheets of duplicating material, except the one actually in use, are always contained in the tray within the box, so that they are at all times protected from damage. Furthermore, the use of a box with a raised top enables the sheets to be clamped thereon in such a manner that only the writing or

drawing to be reproduced is in contact with 20 the sheets to be printed and a sharp impression is hereby obtained.

I claim as my invention:

1. A duplicator comprising a support having depressed end portions to form 25 steps, said steps having depressions, and clips attached to the steps and adapted to be received in the depressions.

2. A duplicator comprising a support, a top for the support having depressed end 30 portions to form steps, and clips hinged to the steps.

3. A duplicator, including a support, a top for the support having depressed end portions to form steps and clips hinged to 35 the steps and foldable thereon.

EDGAR A. OPPENHEIMER.
